ELECTRIC CONTROL SYSTEM

William F. Eames, Pittsburgh, Pa., assignor to
Westinghouse Electric Elevator Company, Chi-
cago, Ill., a corporation of Illinois

Application June 26, 1936, Serial No. 87,361

11 Claims. (Cl. 172—239)

My invention relates to systems for controlling the operation of electrical apparatus, and more particularly to variable voltage systems of control in which direct current motors are operated by the voltage supplied to them from separately excited generators.

In systems of this character (usually known as the Ward Leonard type), the starting, the stopping, the reversing and the speed of the motor are controlled by controlling and varying the excitation of a field winding on the generator. When such systems are provided for operating elevators, hoists, planers and similar machinery and apparatus the motor is usually designed to provide a constant speed regardless of load. A characteristic of this kind of system is that the motor starts sometimes somewhat more slowly than is desired, particularly in the operation of elevators. It is noticeable in the ordinary starting of the elevator car on a trip between floors, and it is very noticeable in leveling operations to bring the car accurately level with a floor when a stop is being made. Some difficulty is occasioned by the residual magnetism in the generator. For instance when the car is being reversed in a leveling operation at a floor the residual magnetism causes the starting of the generator to be slower than when starting in the original direction.

Therefore, it is an object of my invention to provide a control system in which the motor will start quickly and, when used in an elevator system will prevent undue delay in starting the car and also enable it to be leveled quickly and accurately at a floor.

Another object of my invention is to provide for compensating for the residual magnetism in the generator, when starting the motor, and also to provide for compensating for the residual magnetism with one value when starting the motor in the same direction as that in which it has been operating and with another value when starting the motor in a direction reverse to that in which it has been operating, so as to secure practically the same rate of acceleration in each case.

In order to attain these objects, I provide a control system including a small auxiliary direct current dynamo-electric machine which operates as an idling motor while the main motor is stopped, but which is disconnected from its source of energy and temporarily acts as a generator, by reason of its inertia, to supply a boosting current to the auxiliary generator field winding when the main motor starts. The system also

includes novel connecting arrangements for so connecting the dynamo-electric machine in the system that it will always be running and ready for use as a forcing generator when the main motor is started and will compensate for the residual magnetism in the generator in accordance with the forward or reverse starting of the main motor after a stop.

For a better understanding of the invention, reference may be had to the accompanying drawing in which:

Figure 1 is a diagrammatic representation of a control system embodying my invention as applied to an elevator system and is drawn in what is known as the "straight-line" style; and

Fig. 2 is a representation of the relays embodied in Fig. 1.

The illustration of the relays in Fig. 2 shows them with their coils and contact members disposed in horizontal alignment with their positions in the straight-line circuits of Fig. 1, so that the reader may readily determine the identity of any relay, the number and kind of its contact members, and the position of its coil and its contact members in the straight-line circuit.

Referring more particularly to the drawing, an elevator car C is illustrated as suitably suspended in a hatchway (not shown) by a cable 11 which passes over a hoisting drum 12 to a counterweight 13.

The hoisting drum 12 is disposed on a shaft 14 driven by an elevator motor 15. The motor 15 is provided with an armature 15A and a separately excited shunt field winding 15F.

A variable voltage system of control is provided for operating the elevator motor 15 wherein the armature 15A of the elevator motor is connected in loop circuit with the armature GA of a generator G. The generator G is provided with a series field winding GSF and a separately excited field winding GF.

The armature GA of the generator G is driven by means of a main driving motor 17 which includes a squirrel cage rotor 18 and a three-phase, star-connected stator winding 19. The outer leads of the stator winding may be connected to any suitable source of electrical energy represented by the supply conductors L1, L2, and L3.

A direct current exciter E having a shunt field winding EF and an armature E' is disposed on the shaft 20 of the driving motor for providing a direct current source of excitation for building up the excitation of the generator field winding GF at a predetermined rate and then maintain-

ing it at a predetermined value, for energizing the field winding 15F of the elevator motor and for supplying the control circuit of the elevator represented by the conductors L+ and L- with suitable energy for operating the various control switches, relays, etc.

The direction of the excitation current for the field winding GF of the generator may be suitably controlled by means of an up direction switch 10 U and a down direction switch D. The value of the current supplied to the field winding GF may be controlled by a resistor r1 which may be controlled through a high speed relay V.

A car switch CS is provided for the car C for controlling the up and the down direction switches U and D in operating the elevator motor to start and stop the car C. The car switch is provided with contact points 22 and 23 which control the up direction and the down direction switches and with contacts 24 and 25 which control the high speed relay V.

An automatic leveling system is provided for causing the car to level itself with the floor if it overruns or underruns the floor level when a stop is being made at a landing. The leveling apparatus is old and well known in the art, and is here shown as represented by a leveling switch LS having a pair of up contact members LS1 disposed to be operated by a switch arm 38 engaging the upper face of a cam 31 when the car stops just below the floor, and a pair of down contact members LS2 disposed to be operated by a lever 33 engaging the lower face of the cam 31 when the car stops above the floor. Normally the levers 38 and 33 are held in a retiring position by a retiring coil 35 when the car is passing the various floor landings (not shown) but which permits the levers to fall into operating position for leveling the car at a floor whenever the car is stopped at that floor. When the car stops just below a floor, the cam 31 causes the lever 38 to close the contact members LS1 and thereby energizes the up direction switch to cause the car to move upwardly. When the car stops above a floor, the lever 33 is operated by the cam 31 to close the contact members LS2 and thereby energizes the down direction switch to move the car downwardly until it is level with the floor, when the lever 33 slides off the cam 31, thus opening the contact members LS2 and stopping the car.

In systems of this character, it is desirable to have the elevator motor start quickly for any normal run and also for the leveling of the car at a floor whenever a leveling operation is necessary. 65 In order to accomplish this, I have provided a field forcing means by which the field current in the auxiliary field winding GF of the generator G is increased or boosted for a very short period at the instant the direction switch is closed to start the car in response to the leveling device.

The field forcing means includes a small frame direct current dynamo electric machine M which acts as an auxiliary motor or generator, in accordance with the manner in which it is connected in the system. Normally the dynamo M is connected across the control circuits so that it idly rotates as a motor while the car is running or standing. However, when the elevator motor is to be started after a stop, the dynamo M is disconnected from the control circuit and connected to the generator field GF. Its tendency to keep on rotating then causes it to act as a generator to supply a forcing or boosting current to the main generator for the short period it keeps on running under its own inertia after being cut off

from its power. The dynamo M is provided with an armature A which is normally connected across the supply conductors L+ and L- through a current limiting resistor r3. The dynamo M is also provided with a field winding MS which is connected, for constant excitation through a resistor r4 and a hand 36, across the conductors L+ and L-. The stored energy of the dynamo may be varied by moving the hand 36 on the resistor r4 to control its speed.

The motor M may be of any suitable size. The system here illustrated usually employs a voltage of approximately 240 volts on its control conductors and a motor of about 300 watts capacity will be found satisfactory in most cases.

A regulating or voltage-responsive relay R is provided for effecting the disconnection of the dynamo M from the generator field when its boosting voltage falls below a predetermined value. The relay R should be so constructed that it will be energized when the electrical energy impressed upon it amounts to a predetermined value and will be deenergized when the voltage across it drops below a predetermined value. In the present case, the relay R is designed for energization at about 150 volts and deenergization at about 20 volts. The present values are given as an example of suitable values but the relay may be designed to operate at any other suitable voltages.

A field forcing connecting relay T is provided for effecting the disconnection of the dynamo M from the supply conductors L+ and L- while operating as a motor and for connecting it to the auxiliary field winding GF of the generator G to act as a generator in boosting the current in the field winding GF, when the elevator motor is to be started. A re-set relay S is provided for resetting the system to cause the auxiliary motor M to again start in operation, after it has served as a boosting generator.

In addition to providing a forcing current for the generator, it is also desirable to control the forcing current in accordance with the residual magnetism in the generator field after a stop has been made so that a predetermined value of forcing current will be provided when the motor is to resume operation in the same direction and a higher predetermined value of forcing current will be provided when the motor is to resume operation in a reverse direction. A down direction preference relay PD, an up direction preference relay PU and a compensating relay X are provided for this purpose.

It is believed that the invention may be best understood by an assumed operation of the system illustrated in the drawing.

It will be assumed that the car is on an up trip and that the main line switches 48 have been closed to render the control system operative. The closing of the switches 48 energizes the exciter E, the field winding 15F of the motor 15, the armature A and the field winding MS of the dynamo M, the regulating relay R, the re-setting relay S and the up direction preference relay PU. Hence the motor immediately starts operating as an idling motor.

It will be assumed that the car attendant is desirous of operating the car upwardly and rotates the car switch CS in the counter-clockwise direction. The engagement of the switch CS with its contact member 38 energizes the retiring coil 35 of the leveling switch LS and thereby withdraws the levers 38 and 33 from being operated by the engagement of the cam 31 at any floor so

that the car is free to move in its shaft without affecting the leveling apparatus.

The continued movement of the switch CS to engage its contact member 23 energizes the up direction switch U by a circuit extending from supply conductor L+ through CS, 23, U, to L-. This causes the elevator car to start upwardly. The energized switch U closes its contact members U1 thereby energizing the brake coil 6 to release the brake 5 and permit the operation of the hoisting drum 12. The closing of the contact members U2 and U3 energizes the field winding GF of the generator G to effect upward operation of the car by a circuit extending from the supply conductor L+ through U2, GF, U3, r1 to L-. As the car switch is moved further to engage the contact member 25, it thereby energizes the high speed relay V to close its contact members V1 thus eliminating the effect of the resistor r1 in the circuit of the auxiliary field winding Gf and causing the elevator to run at its high speed.

As previously indicated, the dynamo electric machine M was connected and running as a motor at the time the car switch was thrown to its "on" position. At the instant the car switch U was energized it closed its contact members U4 and thereby energized the field forcing connecting relay T. This circuit extended from the supply conductor L+ through U4, S1, T, L-. The energizing relay T immediately opened its contact members T2 and closed its contact members T1. The opening of the contact members T2 disconnected the armature A of the dynamo M from the supply conductors L+ and L- and the closing of the contact members T1 connected the armature A of the dynamo to the circuit through the field winding GF of the generator G. Therefore the dynamo M then ceased receiving energy from the supply conductors L+ and L-, but its armature A was connected to the generator field windings GF and its inertia caused it to continue rotation for a short period of time during which time it operated as a generator supplying a boosting or forcing current to the generator. At the instant the motor M was connected across the main generator field, it had a counter E. M. F. sufficient to deliver energy to the generator field at full voltage. As the energy was delivered by the dynamo, its speed dropped and its voltage also, but it delivered sufficient current to force or boost the generator field to such an extent as to cause the car to start more quickly than it would have started without the operation of the dynamo.

As the speed of the dynamo M dropped, the voltage across the regulating relay R also dropped and, as it reached say, approximately 20 volts, the relay R became deenergized and opened its contact members R1 and R2. The opening of the contact members R2 deenergized the re-setting relay S which in turn opened its contact members S1 and thereby deenergized the field forcing connecting relay T. The deenergized relay T now opened its contact members T1 and closed its contact members T2, thereby disconnecting the auxiliary motor M from the auxiliary field winding Gf but at the same time connecting it across the supply conductors L+ and L- and thereby causing it to again start in rotation, ready for the next starting operation.

It may be noted here that my use of the dynamo M is so arranged that it is always in full operation at the time any starting operation is to be effected, so that it is capable of delivering its boosting current the instant the direction switch

closes its contact members for energizing the generator field in starting the car, either in a landing operation or in a normal car starting operation.

When the up direction switch U was energized, the closing of its contact members U1 energized the residual compensating relay X by a circuit extending from supply conductor L+ through PU3, U1, X, L-. The energized relay X thereupon opened its contact members X1, thus causing the forcing current from the dynamo M to flow through the resistor r2 in moving to the generator field GF. This resistance r2 compensated for the residual magnetism in the generator field in that it prevented the supply of as large a forcing current as would have been supplied if the relay T had not been energized. The amount supplied was sufficient however as the generator was simply resuming operation in the same direction as that in which it had been operating. Hence it is seen that the use of the relay X as connected in the manner described along with the direction relays PD and PU provides for controlling the amount of boosting current in accordance with whether the generator 25 is starting in the same direction or is being reversed.

As the car approaches the floor at which a stop is to be made the car attendant centers the car switch CS, thereby first deenergizing the high speed relay V to reinsert the resistor r1 in the circuit for the field winding GF to reduce the speed of the car and then deenergizes the up direction relay U which opens its contact members U1, thereby deenergizing the compensating relay X 35 and closes its contact members U5, thereby energizing the resetting relay S to prepare the connecting relay T to be again operated to disconnect the dynamo M from operating as a motor and connect it for operating as a generator to supply 40 a boosting current to the field winding GF of the main generator.

It will be assumed that this operation caused the car to stop at the floor but that it overruns the floor and the leveling apparatus now comes 45 into operation to cause the car to level down to the floor at which the stop is to be made. The centering of the car switch not only deenergized the up direction relay U and applied the brake 5, but it also deenergized the retiring coil 35 by disconnecting the contact members 38 and thereby prepared the car for leveling if necessary. The deenergization of the coil 35 permitted the leveling levers 30 and 33 to move into position to engage the cam 31 if the car stopped out of alignment with the floors.

Inasmuch as the car overran the floor, the down leveling lever 33 is engaged by the cam 31 and closes its contact members LS2, thereby energizing the down direction switch D by a circuit extending from supply conductor L+ through 43, LS2, D, L-. The energized down direction switch D closes its contact members D1 thereby releasing the brake 5 from the hoisting drum and closes its contact members D2 and D3, thereby energizing the field winding GF for down direction operation. At the same time the down direction switch D closed its contact members D4, thereby energizing the field forcing connecting relay T which now opens its contact members T2 and closes its contact members T1. The opening of the contact members T2 disconnects the dynamo M from the supply conductors L+ and L- and the closing of the contact members T1 connects it with the auxiliary field 75

windings GF, whereby the dynamo M acts as a generator to supply a boosting current to the windings GF.

The energized switch D also closed its contact members D1 in the circuit for the compensating relay X. Inasmuch as the direction preference relay PU is energized and the direction preference relay PD is deenergized, no circuit is completed at this time for energizing the relay X. Hence the contact members X1 remain closed in the circuit from the motor M to the windings GF. This prevents the resistor r2 from having any effect on the boosting current of the dynamo M and thereby allows the full force of the boosting current to be supplied to the field winding GF. Hence it is again seen that the relay X and its manner of connection provide means for compensating for the residual magnetism in the generator, because in this special instance the generator was being reversed while in the previous instance the generator was merely being started in the same direction. Obviously, upon being reversed, the generator needed the full forcing current that is now provided by the system.

As the rotation of the dynamo M during its action as a generator dies down, its voltage decreases and when it falls to around 20 volts, the regulating relay R becomes deenergized and thereby effects disconnection of the motor M from the generator field and reconnection of it across the control circuit conductors L+ and L-. The deenergization of the relay R opens its contact members R2 thereby deenergizing the resetting relay S which opens its contact members S1 and thereby deenergizes the connecting relay T. The deenergized relay T opens its contact members T1 thereby disconnecting the dynamo M from the generator field GF and closes its contact members T2 thereby connecting the motor M across the supply conductors L+ and L- and again causing it to idle at full speed, ready for the next forcing operation.

The closing of the contact members T2 also again energized the regulating relay R to close its contact members R2 to again energize the resetting relay S. The energized relay S closes its contact members S2 thereby providing a self holding circuit for itself to keep it in condition for preparing the connecting relay T for energization in the next starting operation.

As the car moves downwardly under the control of the leveling apparatus, the lever 33 slides off the cam 31 and is thereby operated to open its contact members LS2. This deenergizes the down direction switch D which opens its contact members D2 and D3 and thereby effects the stopping of the car level with the floor. It may be observed here that the landing apparatus usually compensates for a very short distance, say from 1 to 3 inches, when the car does not land exactly level with the floor. Therefore, it is not necessary to have the high speed relay V come into action in this operation.

By the foregoing it is seen how the forcing current is provided when the car starts in a normal run or starts in a leveling operation and also how the compensating relay operates. The following operation will show how the scheme works when the car starts downwardly and also how the direction preference relays are changed when the direction is changed.

It will be assumed now that a passenger has entered the car and that the car attendant runs the car down to a lower floor. The car attend-

ant throws the car switch CS in its clockwise direction thereby engaging the contact members 22 and 24 successively, thus first energizing the down direction switch D and next the high speed relay V. The operation of the switch D and the relay V closes their contact members D2 and D3 and V1 thereby effecting the starting of the car downwardly through the energization of the field winding GF of the generator G. At the same time the engagement of the contact members 38 by the car switch CS energizes the retiring coil 36 to withdraw the leveling levers to keep them from striking any cams until the car is to be stopped at some floor.

As the car starts downwardly after its down leveling operation, the dynamo M and the relays associated therewith operate to provide a boosting current for the generator field GF through the resistor r2 thereby giving a reduced boosting current. This is effective because the energization of the down direction switch D closes contact members D4 thereby energizing the connecting relay T. The energized relay T opens its contact members T2 thus disconnecting the motor M from the supply conductors L+ and L- and closes its contact members T1 thus connecting the armature of the dynamo M to the generator field GF through the resistor R2. The dynamo M, which has been running as a motor, now operates, by reason of its inertia, as a generator and provides a boosting current for the generator field GF to reduce the time required to get the car under way.

As the speed of the dynamo M drops, its voltage falls and, when it falls to about 20 volts, the regulating relay R becomes deenergized and opens its contact members R2 thereby deenergizing the resetting relay S which, in turn, opens its contact members S1 and deenergizes the connecting relay T. The deenergized connecting relay T now opens its contact members T1 thus disconnecting the motor M from the generator field GF, and closes its contact members T2 thereby reconnecting the armature of the dynamo M and the regulating relay R to the supply conductors L+ and L-. The energized relay R is now conditioned for again effecting the disconnection of the armature of the dynamo M from the generator field GF the next time it operates as a booster.

In starting the car downwardly, the system also automatically effected a change in the preference relays by deenergizing the up direction preference relay and energizing the down direction preference relay for the purpose of so controlling the compensating relay X that the generator field GF will receive a boosting current in accordance with whether it is being reversed or is continuing in its previous direction of operation. This is effected by the energized switch D and the energized high speed relay V opening their contact members D6 and V2 in the circuit for the up preference relay PU. The deenergized relay PU closes its contact members PU1 thereby energizing the down preference relay PD by a circuit extending from supply conductor L+ through U6, PU1, PD, L-. The energized relay PD closes its contact members PD3 and thereby energizes the compensating relay X which in turn opens its contact members X1, thus forcing the boosting current from the dynamo M to go through the limiting resistance r2 to the generator field GF thus causing a compensating effect on the boosting current which restricts its value to the value suitable for boost-

ing the generator when it is resuming operation in the same direction.

As the car approaches the floor desired by the passenger, the car attendant centers the car switch CS thereby deenergizing the high speed 5 relay V to close its contact members V1 and thus reduce the speed of the car, and to also deenergize the switch D to effect the stopping of the car at the floor desired. It will be assumed that at this floor the car does not overrun or underrun but stops level with the desired floor and, therefore, that no leveling operation is necessary.

By reason of the foregoing description, it will 15 be seen that the apparatus is arranged for effecting a smooth operation of a variable voltage system and provides a means for giving a boosting current to the generator field at the instant the motor is to be started, and that this boosting 20 current is given regardless of whether the car is starting on an ordinary run or whether it is starting in a leveling operation. It will also be seen that the circuits and apparatus provide for so controlling the amount of the boosting 25 current that the generator field will receive a larger boosting current when its direction of operation is being reversed than when it is being started in the same direction as that in which it has been operating.

30 Although the invention has been disclosed in connection with a variable voltage system for an elevator, it will be readily understood it may be of value in many other installations of variable voltage systems; for instance, it will prove of 35 considerable value in connection with the operation of planers and in connection with the operation of many hoists as well as in connection with other machinery and apparatus.

Although I have illustrated and described only 40 one specific embodiment of my invention, it is to be understood that many modifications thereof and changes therein may be made without departing from the spirit and scope thereof.

I claim as my invention:

45 1. In an electric system, a generator provided with means including a field winding for exciting the same, a dynamo-electric machine, means for connecting the dynamo-electric machine to a source of electric power for operation as a motor when said field winding is deenergized and for disconnecting it from said power and electrically connecting it to said field winding for operation as a generator when said field winding is being excited.

50 2. In an electric system, a generator provided with a field winding, means for connecting the generator field winding to a source of electric energy for building up the excitation of the field winding at a predetermined rate, a dynamo-electric machine, means for electrically connecting the dynamo-electric machine to a source of power for rotating it as a motor, and means responsive to operation of the field winding connecting means for electrically disconnecting the dynamo-electric machine from its source of power and for electrically connecting it to said field winding whereby the inertia of said machine will cause it to act as a generator to deliver electrical energy to said field winding for increasing the rate of excitation during the building up period.

55 3. In an electric system, a generator provided with a field winding, means for connecting the generator field winding to a source of electric energy for building up the excitation of the field

winding at a predetermined rate, a dynamo-electric machine, means for electrically connecting the dynamo-electric machine to a source of power for rotating it as a motor, means responsive to operation of the field winding connecting means 5 for electrically disconnecting the dynamo-electric machine from its source of power and for electrically connecting it to said field winding whereby the inertia of said machine will cause it to act as a generator to deliver electrical energy 10 to said field winding for increasing the rate of excitation during the building up period, and means responsive to deceleration of the dynamo-electric machine while it is acting as a generator for electrically disconnecting it from said field 15 winding.

4. In an electric system, a generator provided with a field winding, means for connecting the generator field winding to a source of electric energy for building up the excitation of the field 20 winding at a predetermined rate, a dynamo-electric machine, means for electrically connecting the dynamo-electric machine to a source of power for rotating it as a motor, means responsive to operation of the field winding connecting means 25 for electrically disconnecting the dynamo-electric machine from its source of power and for electrically connecting it to said field winding whereby the inertia of said machine will cause it to act 30 as a generator to deliver electrical energy to said field winding for increasing the rate of excitation during the building up period, means responsive to deceleration of the dynamo-electric machine while it is acting as a generator for electrically disconnecting it from said field winding, and 35 means responsive to operation of said last-named means for electrically reconnecting said dynamo-electric machine to its source of power.

5. In an electric system, a generator provided with a field winding, means for connecting the generator field winding to a source of electric energy for building up the excitation of the field winding at a predetermined rate, a dynamo-electric machine having an armature and a field winding, means for electrically connecting the 45 armature and field winding of the dynamo-electric machine to a source of power for operating it as a motor, means responsive to operation of the connecting means of the generator field winding for disconnecting the armature of the dynamo-electric machine from its source of power and connecting it to the generator field winding whereby the inertia of the dynamo-electric machine will cause it to act as a generator for boosting the starting of the generator, a device responsive to a predetermined decrease in voltage of the dynamo-electric machine while operating as a generator for disconnecting said armature from the generator field, and means responsive to operation of the voltage responsive device for 50 reconnecting the armature to its source of power to cause the machine to resume operation as a motor.

6. In an elevator system, a generator provided with a field winding, means for connecting the field winding to a source of electric energy for building up the excitation of the field winding at a predetermined rate, a dynamo-electric machine, means responsive to operation of the connecting 65 means for effecting operation of the dynamo-electric machine for delivering electric energy to said field winding to increase its rate of excitation during the building up period, and means responsive to the direction of energization of said generator for controlling the amount of electrical 70 energy for building up the excitation of the field

energy delivered from said dynamo-electric machine to said field winding in accordance with the direction in which said generator is energized after being deenergized.

5. 7. In an electric system, a generator provided with means including a field winding for exciting the same, a dynamo-electric machine, means for connecting the dynamo-electric machine to a source of electric power for operation as a motor 10 when said field winding is deenergized and for disconnecting it from said power and electrically connecting it to said field winding for operation as a generator when said field winding is being excited, and means responsive to the direction of 15 energization of the generator for controlling the amount of energy delivered by said dynamo-electric machine operating as a generator to said field winding in accordance with the direction of energization of the generator when it is energized 20 after being deenergized.
8. In an electric system, a generator provided with a field winding, means for connecting the generator field winding to a source of electric energy for building up the excitation of the field 25 winding at a predetermined rate, a dynamo-electric machine having an armature and a field winding, means for electrically connecting the armature and the field winding of the dynamo-electric machine to a source of power for operating 30 it as a motor, means responsive to operation of the connecting means of the generator field winding for disconnecting the armature of the dynamo-electric machine from its source of power and connecting it to the generator field 35 winding whereby the inertia of the dynamo-electric machine will cause it to act as a generator for boosting the starting of the generator, a resistor, and means responsive to the direction of energization of the generator for connecting said 40 resistor in the circuit connections between the armature and the generator field winding when the generator is being energized in the same direction, and for eliminating the effect of said resistor from said circuit when the generator is 45 energized in a direction opposite to that in which it has been energized whereby the boosting effect of the dynamo-electric machine of the generator field is controlled in accordance with the residual magnetism in said field when the generator is 50 being energized.

9. In an electric system, a generator provided with a field winding, means for connecting the field winding to a source of electric energy for building up the excitation of the field winding at 55 a predetermined rate, a control system for said generator, a dynamo-electric machine having an armature and a field winding, a resetting relay responsive to an inoperated condition of the control system for connecting the machine to a

source of power for operating it as a motor, a field forcing relay responsive to operation of the control system in starting the generator for disconnecting the armature of the machine from its source of power and electrically connecting it to the generator field winding for increasing said predetermined rate of excitation of the generator field winding, a voltage relay responsive to a predetermined drop in the voltage of the machine operating as a generator for operating said resetting relay, means responsive to operation of the resetting relay for operating the field forcing relay, means responsive to the operation of the field forcing relay for disconnecting the machine armature from the generator field and reconnecting it to its source of power whereby the machine again operates as a motor, a plurality of direction relays responsive to the direction of energization of the generator, a resistance element associated with the circuit for connecting the armature to the generator field, and a residual compensating relay responsive to operation of the direction relays and the control means for connecting the resistor in circuit between the armature and generator field when the generator is being energized in the same direction of operation in which it has been energized and for eliminating the effect of the resistor in the circuit between the armature and the generator field when the generator is being energized in a direction opposite to the direction in which it has been energized.

10. In an electric system, a generator provided with a field winding for exciting it, control means for connecting the field winding to a source of power to start excitation, a dynamo-electric machine, means for connecting the machine to a source of power to place it in operation before operation of said control means, and means responsive to operation of the control means for disconnecting the machine from its source of power and electrically connecting it to said field winding for operation as a generator when excitation of said field winding is started.

11. In an electric system, a generator having a field winding for energizing said generator, means for controlling the direction and amount of excitation of said generator field winding, means comprising a dynamo-electric machine responsive to said generator field controlling means for delivering a predetermined amount of electric energy for said generator field for one direction of excitation, and means responsive to operation of the control means to operate the generator in another direction for controlling the output of the dynamo-electric machine to deliver to the generator field an amount of energy different from said predetermined amount.

WILLIAM F. EAMES.
